UNITED STATES PATENT OFFICE.

THEODORE J. SMULSKI, OF CHICAGO, ILLINOIS, ASSIGNOR TO JOHN W. ANDERSON, OF GARY, INDIANA.

CALCULATING DEVICE.

Application filed February 2, 1923. Serial No. 616,544.

My invention relates to improvements in a calculating device, and more particularly to a device of the kind described which will be extremely compact so that all of the working parts thereof may be mounted in a watch case or the like and carried in the vest pocket of the user, where it will be handy for use at all times.

Another object of my invention is to provide a device of the kind described which will be neat and attractive in appearance, simple in construction, extremely accurate in use and efficient and satisfactory wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a plan view of the device as enclosed within a watch case;

Fig. 2 is a section taken substantially on the line 2—2 of Fig. 1;

Fig. 3 is a face plan view of the device with the front cover of the watch removed, for the purpose of clearer illustration;

Fig. 4 is a rear view of the device as shown fixed in the watch case, with the rear cover of the case shown broken away;

Fig. 5 is a section taken substantially on the line 5—5 of Fig. 4, but with the rear cover in place;

Fig. 6 is a section taken substantially on the line 6—6 of Fig. 7;

Fig. 7 is a section taken substantially on the line 7—7 of Fig. 6;

Fig. 8 is a section taken substantially on the line 8—8 of Fig. 9;

Fig. 9 is a section taken substantially on the line 9—9 of Fig. 8;

Fig. 10 is a section taken substantially on the line 10—10 of Fig. 2;

Fig. 11 is a section similar to that shown in Fig. 10, but with the partition plate shown therein removed;

Fig. 12 is a plan view of one of the number disks;

Fig. 13 is a plan view of one of the partition disks, and

Fig. 14 is a fragmentary perspective of one of the carry-over elements.

In the drawings, wherein I have illustrated the preferred embodiment of my invention, 60 1 indicates a case of any preferred size, shape, design and material, having a bored stem 2 extending to one side thereof and in which is frictionally and removably positioned a pin 3 having a knob or knurled head 65 4, said pin serving to control the spring catch for holding the watch case closed.

I have shown the casing 1 as a watch case, but it is to be understood that any special form of housing or casing may be used, if 70 so desired.

A supporting member having a peripheral flange 5 with a web 6 extending across said flange is provided to carry the parts of the device, said web portion 6 extending obliquely of the median plane of the flanged part 5 and having a series of annular steps or shoulders 7 carried thereon, progressively varying in diameter, each of the shoulder portions 7 being circular in form, the centers of each of the shoulder portions 7 being offset from the center of the flange circle 6 and all of said mutually eccentrically spaced portions having a point in common at their circumferences. The member 5—6 is pref- 85 erably held rigidly in position in the casing by means of a cross-bar 8, as shown.

Rotatably arranged on each of the stepped portions 7 are a series of peripherally notched or toothed dials or disks, said disks 90 being of progressively varying diameter so that all of them have a point in common at their circumferences. Any number of disks may be used, and in the construction shown there are five disks, 9, 10, 11, 12 and 13, each 95 of said disks having a plurality of sets of digits thereon, each set marked or numbered from 0 to 9 inclusive, the larger of said disks representing the lowest order of the calculating system and in the present instance will 100 be termed the unit order; the next disk being the tens order, the next the hundreds order, and so on. Two sets of digits are provided on each of the dials in the embodiment

shown, but it is to be understood that any number of sets of digits may be arranged thereon. The disks 9-13, inclusive, are notched or toothed on their peripheries as hereinbefore noted, to correspond with the number of digits marked thereon.

Intermediate the adjacent disks are arranged spacing members or plates 14, substantially of circular form so as to conceal 10 the digital markings on the disks, the same secured to the stepped portions 7 by screws 15 or any other suitable or equivalent fastening means. Each of the members 14 has a portion of its periphery cut away for substantially 15 half its circumference so as to provide stops or shoulders 16 at the ends of said cut-away portion, and intermediate the end of said cut-away portion the member 14 is provided with a reference notch 20 or opening 17 whereby a digit on the numbered disks may be viewed successively.

When the parts are arranged in the position shown all of the numbers or digits on the dials are concealed except the single 25 digits visible through the notches 17. Diametrically opposite the reference notch 17 the members 14 are provided with a circumferentially extending opening 18, and extending circumferentially from adjacent 30 each end of the opening 18 are peripheral flanges 19-19', formed on the disk 14, as shown, the adjacent ends of said flanges being spaced apart. Intermediate the ends of the flanges and projecting from the other 35 face of the member 14 so as to extend in a direction opposite to the flanges 19-19' is a cam 20, said cam arranged to lie substantially on the diametrical line passing through the notch 17 and the opening 18. A portion of the disk carrying the flange 40 19' has been cut away so as to form said flange into a spring member, the free end of said spring member having a detent 21 formed thereon adapted to releasably engage the notched periphery of the disks 9 to 13.

The top member 14' has an opening 17 therein but is substantially imperforate otherwise except for the opening through 50 which a screw 22 is inserted for securement to the web 6. The edges 23 of the member 14' do not extend radially outwardly but extend substantially diagonally so as to overlie the flanges 19-19' of the plates 14, and leaving the series of shoulders 16 of the disks 14 visible.

A series of digits 24 is provided on the member 14' and a similar series of digits 25 is arranged to run in the reverse order adjacent the periphery of the lowest order of the disks 9, the terminal digits of each of said series being positioned adjacent the stops 16.

Extending diagonally across each of the 65 toothed disks are recesses 26, the recesses di-

verging in depth from their inner to their outer ends. Resilient cam members 27 are adapted to seat in each of the recesses 26, said cam members being held in place in any suitable manner and preferably by means of a ring or annulus 28 arranged to engage with each of the toothed disks so as to be nonrotatable relatively thereto, as shown in Figs. 12 and 14. With the parts arranged as shown in the drawings a movement of 75 any of the lower order of disks through its sequence of one of its sets of digits will cause the next higher order of disks to be moved through one digital position.

The flexible cams 27 carried by the toothed disks will rotate therewith, being held down by the flanges 19-19' of the plate 14 thereabove, until such cams engage with the fixed cams 20 carried by the web 6 and the plates 14, whereupon such cam 27 will be lifted to extend through the opening 18 in the plate 14 and engage between a pair of adjacent teeth of the next higher order of disks. The continued rotary movement of the lower order disk through the distance 90 between adjacent teeth or digits will move the higher order disk therewith through the same distance, said cam 27 being released from engagement with the higher order of disk after a movement through said predetermined distance.

This "carrying-over" operation is clearly shown in Figs. 6-9, inclusive. In Fig. 6, all of the yieldable cams 27 are below the disks 14, between them and the next higher order 100 of numbered disks, while in Figs. 8 and 9 the yieldable cam 27 has been lifted by the cam 20 so as to extend through the opening 18 and into the space between the notches of the numbered disk 11 so that further 105 movement of the notched member 10 will cause similar movement of the member 11 through the distance between adjacent digits or teeth, the flexible cam 27 releasing its engagement with the numbered disk 11 as 110 soon as the flexible cam reaches the far side of the stationary cam 20.

The operation of the device is as follows:

Assuming that it is desired to perform addition, let us say, of the numbers 27 and 115 13, then with the parts in the position shown in Fig. 3 the disk corresponding to the order of tens will be moved 2 teeth and the unit disk moved through 7 teeth, this movement being effected by any suitable means 120 or instrument, as desired, the detent 21 yieldably engaging the teeth and preventing accidental overrunning. For this purpose the removable pin 3 may be used by engaging it in the space between the teeth of the disk 10 most closely adjacent the numeral 2 of the reference series 25 and moving the disk forward (to the left) until the pin 125 comes in contact with the stop 16, whereupon the pin is withdrawn. The unit disk is 130

similarly engaged in the space most closely adjacent the digit 7 of the series 25 and the disk 9 is forwardly moved until the pin 3 engages the stop 16, whereupon the pin 3 is withdrawn. The indicator dial will then read 00027. Now to add 13 to the 27, the pin 3 is first inserted in the disk 10 in the space most closely adjacent the numeral 1 of the series 25 and said disk moved through one tooth or until the pin engages the stop 16. Then the unit dial or disk is moved in the same manner through three teeth, that is, the pin engages it adjacent the space between the teeth of said dial nearest the number 3 of the series 25, whereupon the visible number will be 00040, indicating that the sum of 27 and 13 equals 40.

Subtraction may be performed with the device, except that in this instance the series 20 of digits 24 is to be used as the guide for the proper insertion of the pin 3, instead of the series 25.

In case it is desired to use the device as a counter, a pin 30 may be arranged at any suitable point on the casing, said pin having its inner end adapted to engage the teeth of the lowest order of disks and having an enlarged head 31 whereby the pin may be operated. A spring 32 is interposed between the pin 30 and the casing so as to normally press the pin outwardly of the teeth of the disks.

It will be noted that the disks are obliquely arranged or mounted, thereby enabling them to be more easily operated and read, because the visible digits of the disks 9-12 will then be substantially in a plane most nearly parallel to the median plane of the watch case.

One of the important advantages of constructing the device in the manner described is that there may be a certain small amount of movement lost on each wheel to allow for engaging and disengaging during carrying so that the numerals to be read are always aligned and the reading may be accurately made. In other words, during the carrying there will be no lagging but the device will be accurate at all times.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A calculator comprising a series of movable disks of progressively varying diameters and orders mounted above one another with their centers spaced so that all of said disks have a point in common at

their circumference, each of said disks having a series of numbers thereon and a recess therein, and yieldably-held means between each pair of adjacent disks and engageable in the recess in the adjacent disk 70 to carry-over said adjacent disk when the other of said disks has been moved a predetermined amount and automatically disengaging from said recess as soon as the carrying-over has been effected. 75

2. A calculator comprising a series of movable disks of progressively varying diameters and orders mounted above one another with their centers spaced so that all of said disks have a point in common at 80 their circumference, each of said disks having a series of numbers thereon and a recess therein, and yieldably-held means between each pair of adjacent disks and engageable in the recess in the adjacent disk to carry-over said adjacent disk, when the other of said disks has been moved a predetermined amount, and guide means for automatically positively disengaging said yieldably-held means from said recess as soon as the 85 carrying-over has been effected.

3. A calculator comprising a series of movable notched disks of progressively varying diameters and orders mounted above one another with their centers laterally spaced so that all of said disks have a point in common at 90 their circumference, each of said disks having a series of numbers thereon and provided with a radial recess therein, a partition above each disk, and provided with a yieldable detent engageable successively with the notches in said disks to yieldably hold them against accidental movement and also provided with an elongated aperture therethrough and with a 95

stationary guide cam thereon adjacent said aperture, and a yieldable cam engageable with said stationary cam, said yieldable cam mounted in the recess in each of said disks and movable therein into said elongated 100 recess in the partition, whereby when one of said disks is moved through a predetermined distance, said yieldable cam will be engaged and guided in its movement by the stationary cam on the partition to carry-over an adjacent disk of the next order, and be guided out of carrying engagement after a movement through the distance between adjacent digits. 110

4. A calculator comprising an enclosing case, a support mounted in said case and having a series of axially spaced annular shoulders of progressively varying diameter formed thereon, each of said annular shoulders having its center laterally offset from the centers of the other shoulder, all of said shoulders at one point of their circumferences lying in a line parallel to the axes of the shoulders, means for mounting said support obliquely in said case, a toothed annulus 120

125

130

4

rotatably mounted on each of said shoulders and provided with a plurality of series of digits thereon, there being one digit for each tooth, said disks adapted to be actuated with a stylus in the notches, means for covering said disks so that only one series of digits will be visible, partitions above each disk for covering them so that only one digit thereon will be visible, and stops for engaging the stylus used for actuating said disk and limiting the continuous movement thereof.

In testimony whereof, I have hereunto signed my name.

THEODORE J. SMULSKI.
